UNITED STATES PATENT OFFICE.

ANTON CERVENY, OF BELLEWOOD, ILLINOIS.

SWINGING-DOOR OR GATE-OPENING MECHANISM.

Application filed November 9, 1922. Serial No. 599,849.

To all whom it may concern:

Be it known that I, ANTON CERVENY, a citizen of Czechoslovakia, residing at Bellewood, in the county of Cook and State of Illinois, have invented certain new and useful Improvements in Swinging Door or Gate Opening Mechanisms, of which the following is a specification.

This invention relates to certain new and 10 useful improvements in swinging door or gate opening mechanisms, and has particular reference to the provision of simple and improved means for opening swinging doors or gates automatically by the weight of a 15 vehicle approaching said gate operating a compressible platform.

The primary object of the invention is to generally simplify and improve devices of the above kind whereby the same may 20 be readily placed into practical use.

With these general objects in view and others that will appear as the nature of the invention is better understood, the same consists in the novel construction, combination 25 and arrangement of parts hereinafter more fully described, illustrated in the accompanying drawings, and pointed out in the appended claims.

In the drawings forming a part of this 30 application and in which like designating characters refer to corresponding parts throughout the several views:—

Fig. 1 is a transverse sectional view taken on line I—I of Fig. 3 and showing the 35 present invention embodied in mechanism associated with a swinging gate,

Fig. 2 is a longitudinal sectional view taken upon line II—II of Fig. 3,

Fig. 3 is a top plan view partly broken 40 away of a gate mechanism constructed in accordance with the present invention,

Fig. 4 is a vertical transverse sectional view taken on line IV—IV of Fig. 2 partly broken away,

Fig. 5 is a plan view showing the operating lever and gearing of the mechanism partly broken away,

Fig. 6 illustrates a latching means which 45 may be provided for holding the gate in open position, and

Fig. 7 is a top plan view of the device shown in Fig. 6.

Referring more in detail to the several views, the present invention is shown associated with a swinging gate 5 of a fence 55 construction 6, although the invention may be utilized in connection with swinging closures of all kinds such as barn doors or the like.

In accordance with the present invention 60 the gate 5 is provided with a vertical shaft 7 by means of which the gate is pivotally mounted at one end for horizontal swinging movement when associated with the brackets 8 of ordinary form, and the shaft 65 7 depends below the bottom of the gate 5 and enters a suitable large casing 9 which is sunk into the ground so that the top wall 10 of said casing lies flush with the ground line, as shown clearly in Fig. 1. 70 The gate post 11 adjacent the shaft 7 supports a suitable bracket 12 which projects inwardly through a slot 13 provided in the adjacent side wall of the casing 9, and this bracket 12 has the lower end of the shaft 7 journaled therein while the inner free end of one arm of the bracket is upturned 75 as at 14 to provide a slide rest for a horizontal swinging lever 15 which has its inner end pivoted as at 16 upon a suitable post or standard 17 mounted within and upon the bottom of the casing 9. A suitable bur pinion 18 is fixed upon the lower end of the shaft 7 and meshes with a segment gear 19 which is rigid upon the free adjacent end 80 of the lever 15, the segment gear 19 being of slightly curved rack bar form and it will thus be seen that when the lever 15 is swung in one direction, the pinion 18 will be rotated together with the shaft 7 for opening 85 the gate 5.

In order that the approaching vehicle may automatically open the gate upon approach to the latter, the lever 15 is properly operatively connected to a normally 90 raised spring pressed platform 20 over which the vehicle must pass in approaching the gate.

In the preferred form the platform 20 is 95 preferably hinged along its edge which is 100

- farthest from the gate 5, and is provided with a cleat 21 at its opposite edge to which are attached a plurality of depending guide rods 22 which project downwardly through suitable openings 23 in the top wall 10 of the casing 9 and which are slidably disposed through further openings provided in transverse guide bar 24 which is suitably mounted horizontally beneath the top wall 10 of the casing upon angle brackets 25. Each guide rod 22 is surrounded by a helical compression spring 26, one end of which bears upon the upper surface of the guide bar 24 and the other end of which bears against the under surface of the cleat 21. In this manner the platform 20 is normally held raised at its inner or free edge and with uniform distribution of spring pressure from side to side thereof.
- 20 Centrally of the cleat 21 another rod 27 is secured, and this rod depends from the cleat through aligned openings in the top wall 10 and the guide bar 24 and has its lower end in contact with the upper surface of the adjacent end of the bell crank lever 28 which is pivoted on a suitable bracket 29 for vertical swinging movement, the bracket 29 being suitably fixed upon the bottom casing 9. The arm of the lever 28
- 25 which engages the lower end of the rod 27 is preferably longer than the arm of said lever which projects toward the lever 15, and the latter arm is connected to the lever 15 by means of a pull rod or link 30 with the point of attachment of the link 30 with the lever 15 between the ends of the latter lever.
- 30 In operation, the vehicle will depress the platform 20 and cause downward movement of the rod 27 while compressing the springs 26 so that bell crank lever 28 is swung upon its pivot from the full line position of Fig. 2 to the dotted line position thereof and through the link 30, a pull towards the vehicle is exerted upon the lever 15 so as to cause opening movement of the gate 5 through the gearing described. As soon as the vehicle leaves the platform 20, the springs 26 will exert their force to return
- 35 the platform again to raised position and to allow the gate to immediately swing closed. The swinging of the gate to closed position automatically may be accomplished by slightly tilting the shaft 7 so that the same is not truly vertical.
- 40 In case it is desired to retain the gate 5 in open position, the said gate may be provided with a suitable form of spring pressed latch 31 at its free end engageable with a keeper 32 mounted upon a post 33 which is positioned at one side of the casing 9, the arrangement being such that the gate will not quite swing open far enough to engage the latch 31 with the keeper 32 upon
- 45 operation of the platform 20, but a slight

further manual pull of the gate toward open position will effect this latching relation between the latch 31 and the keeper 32 for the purpose referred to. A suitable cleat 34 which is best seen in Fig. 3 may be provided to properly limit the movement of the gate to closing position.

From the foregoing description it is believed that the construction and operation as well as the advantages of the present invention will be readily understood and appreciated by those skilled in the art.

Minor changes may be made without departing from the spirit and scope of the invention as claimed.

What is claimed as new is:—

1. In combination with a horizontally swinging closure having a vertical pivot shaft fixed to one end thereof and depending below the latter, a casing adapted to be mounted with its top wall flush with the floor line of the closure and into which said shaft projects, a pinion upon the lower end of said shaft within the casing, a bracket within the casing having the shaft journaled therein, a horizontally swinging lever pivoted at one end upon a vertical axis within the casing and having a rack bar of ar-
cuate form rigid upon the other end thereof in mesh with said pinion, said bracket forming a slide rest for said rack bar, a spring raised depressible platform, and operative connections between said platform and said lever including a link connected to the lever intermediate its ends, a horizontal guide bar fixed transversely in the casing, said operative connections embodying a plurality of guide rods fixed to the platform and slidably projecting through the top of the casing and said guide bar, and helical compression springs interposed between the guide bar and the platform and each encircling one of said guide rods.

2. In combination with a horizontally swinging closure having a vertical pivot shaft fixed to one end thereof and depending below the latter, a casing adapted to be mounted with its top wall flush with the floor line of the closure and into which said shaft projects, a pinion upon the lower end of said shaft within the casing, a bracket within the casing having the shaft journaled therein, a horizontally swinging lever pivoted at one end upon a vertical axis within the casing and having a rack bar of ar-
cuate form rigid upon the other end thereof in mesh with said pinion, said bracket forming a slide rest for said rack bar, a spring raised depressible platform, operative connections between said platform and said lever including a link connected to the lever intermediate its ends, a horizontal guide bar fixed transversely in the casing, said operative connections embodying a plurality of guide rods fixed to the platform

and slidably projecting through the top of the casing and the guide bar, and the casing and said guide bar, helical compression springs interposed between the said last named guide rod bears and the 10 guide bar and the platform and each encircling one of said guide rods, said operative connections further including a still further guide rod slidably extending through

the top of the casing and the guide bar, and a bell crank lever upon one end of which said last named guide rod bears and the 10 other end of which is connected to said first named lever.

In testimony whereof I affix my signature.
ANTON CERVENY.
